UNITED STATES PATENT OFFICE

157,800

SHOPPING BAG OR SIMILAR ARTICLE

Betty Sommer, Elmhurst, N. Y.

Application May 28, 1949, Serial No. 2,929

Term of patent 7 years

(Cl. D87—3)

To all whom it may concern:

Be it known that I, Betty Sommer, a citizen of the United States of America, and residing at Elmhurst, county of Queens, city and State of New York, have invented a new, original, and ornamental Design for a Shopping Bag or Similar Article, of which the following is a specification, reference being made to the accompanying drawing, forming part thereof.

Fig. 1 is a view, partly in perspective, of a shopping bag embodying my new design, illustrating the shopping bag in an open position;

Fig. 2 is a top plan view thereof as shown in Fig. 1.

Fig. 3 is a front perspective view of the shopping bag in closed position; and

Fig. 4 is a rear perspective view thereof as shown in Fig. 3.

The dominant feature of this invention resides in the portions shown in full lines.

I claim:

The ornamental design for a shopping bag or similar article, substantially as shown and described.

BETTY SOMMER.
